(Cl. D44—15)

To all whom it may concern:

Be it known that I, A Baker Barnhart, a citizen of the United States, residing in the city of New York, State of New York, have invented a new,
original, and ornamental Design for a Covered Dish or Similar Article, of which the following is a specification, reference being had to the accompanying drawing, forming a part hereof.

Fig. 1 is a plan view of a covered dish or similar article showing my new design.

Fig. 2 is a partial sectional side view through line 2—2 of Fig. 1.

I claim:

The ornamental design for a covered dish or similar article, as shown.

A BAKER BARNHART.
